Patented June 6, 1967

207,848

COMBINED NOZZLE AND SHIELD

John A. Royer, Fresno, Calif., assignor to Buckner
Industries, Inc., a corporation of California

Filed Oct. 4, 1965, Ser. No. 87,290

Term of patent 14 years

(Cl. D31—3)

FIG. 1 is a top plan view of a combined nozzle and shield showing my new design.

FIG. 2 is a bottom plan view thereof.

FIG. 3 is a side elevation thereof, the opposite side of my combined nozzle and shield being identical to the side shown.

FIG. 4 is a front elevation thereof.

FIG. 5 is a rear elevation thereof.

FIG. 6 is a perspective thereof.

FIG. 7 is a cross-sectional view thereof, taken on the line 7—7 of FIG. 3.

I claim:

The ornamental design for a combined nozzle and shield, as shown and described.
